EYEGLASS FRAME OR SIMILAR ARTICLE

Alexander Kono, Woodside, N.Y., assignor to Kono Manufacturing Co. Inc., Woodside, N.Y., a corporation of New York

Filed Aug. 3, 1964, Ser. No. 81,124

Term of patent 14 years

The portion of the term of the patent subsequent to Feb. 9, 1979, has been disclaimed

(Cl. D57—1)

FIG. 1 is a front elevational view of an eyeglass frame or similar article, showing my new design;

FIG. 2 is a top plan view thereof; and

FIG. 3 is a side view thereof.

I claim:

The ornamental design for eyeglass frame or similar article, substantially as shown.
